UNITED STATES PATENT OFFICE

WILHELM K. MOLL, OF CHICAGO, ILLINOIS, ASSIGNOR TO DITTO, INCORPORATED, OF CHICAGO, ILLINOIS, A CORPORATION OF WEST VIRGINIA

HECTOGRAPH MACHINE

Application filed October 9, 1929. Serial No. 398,326.

The invention relates to duplicating machines of the type employing a gelatine matrix on which a master sheet is first impressed and from which copies to the desired number are taken, the master and copy sheets being impressed on the matrix by rollers journaled in a platen carriage travelling over the matrix.

Duplicating machines of the type commonly known as hectograph machines are used extensively in office work wherein it is desired to secure a number of duplicates of bills, time sheets or the like, and are equally efficient in duplicating a time sheet the maximum size of the machine or in duplicating a gas or electric bill of consequently much smaller size. In duplicating a gas bill, for example, the bill or master sheet is first inserted between the rollers journaled in the platen carriage which presents the marginal edge of the sheet into contact with the gelatine surface. Upon operation of the carriage to travel over the gelatine surface, the sheet is fed from the rollers upon the gelatine which receives the desired impression, after which the sheet is stripped from the surface by the return travel of the carriage. The desired number of copies may be duplicated in a similar manner and the operation repeated employing a master sheet of probably larger size. Heretofore in these operations it has been left entirely to the judgment of the operator as to the required stroke the carriage should take to impress the full length of the sheet or copy upon the gelatine, and often the carriage is worked so far that the copy is lost between the rollers and remains in adhesion upon the gelatine surface. This requires the operator to strip the copy from the gelatine by hand. It is for use in the operation of the machines when duplicating a variety of master sheets of different sizes, as described, that the improvements of the present invention have been particularly designed, and one of the primary objects of the invention is to increase the efficiency of the machines when employed for such work by providing a novel carriage stop and indexing means for ren-

dering the operation of the carriage positive and reliable at all times.

Another object of the present invention is to provide a carriage stop and indexing means for hectograph machines that will allow for a wide range in the travel of the platen carriage.

Yet another object is to provide a carriage stop and indexing mechanism for hectograph machines having novel actuating means for the latter which may be thrown into and out of engagement at the will of the operator.

A further object is to provide a carriage stop and indexing means that will be simple and durable in construction, economical to manufacture, easy to manipulate, and positive and reliable in operation.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a side elevation of a hectograph machine embodying the features of the present invention;

Figure 2 is a fragmentary top plan view showing the stop and indexing means as applied to the platen carriage;

Figure 3 is a sectional view taken substantially along line 3—3 of Figure 1 showing in detail the stop wheel and pawl arrangement; and

Figure 4 is a sectional view taken substantially along line 4—4 of Figure 3 showing the stop wheel and indexing member.

In carrying the invention into effect in the embodiment thereof which has been selected for illustration in the accompanying drawings, a frame is provided having side members 10 within which are journaled the gelatine rolls 12 through suitable spindles 14. A flat platen (not shown) is mounted within the side members 10 and forms the printing bed of the machine by having the

gelatine band 16 supported thereon. A platen carriage, designated in its entirety at 18, is adapted to travel back and forth over the exposed surface of the gelatine band 16, and, to facilitate such movement, is provided with a guiding extension 20 which has sliding engagement with the guide rod 22 mounted on the side members 10 through the supports 24.

10 The carriage stop mechanism comprises a stop wheel 26 mounted for rotation on the bearing 28 which is securely fastened to the carriage extension 20 by means of a set screw 29 so that the stop wheel is adapted for 15 rotation on the guide rod 22 as well as sliding movement in accordance with the movement imparted to the carriage. The stop wheel forms a supporting means for a plurality of stop rods 30 of predetermined lengths which are secured to the wheel at spaced intervals around its periphery by means of the threaded ends 31. The rods 30 act as stop means for arresting the rearward movement 20 of the carriage by engaging the bumper 32 secured to the sleeve 34 on the guiding rod 22. A pawl 36 is provided pivoted at 38 on the rod 39 for locking the stop wheel in a set position so that a selected stop rod may be held in alignment with the bumper. The 25 free end of the pawl 36 has locking engagement in the grooves 40 by abutment with the teeth 42 provided on the circumference of the stop wheel 26, and is maintained in a particular groove by the tension exerted 30 by the spring 44 which has one end secured to the pawl and the other to the carriage extension 20 by means of the screw 47.

The indexing means shown in Figure 4 consists of a bracket plate 48 which is secured by suitable bolts to a stationary part 40 of the frame of the machine, generally the side members 10, and has mounted therein a plunger 50 held in proper position by the spring 52. For retracting the plunger 50 45 against the tension of the spring 52 a sliding block 54 is provided having a wedge shaped outer surface 56 against which a pin 58 is adapted to engage in the movement of the block when actuated by the operator 50 through the handle 60.

In the operation of the parts as thus described, the platen carriage as disclosed in Figure 2 is in its extreme forward position nearest the operator, in which position the 55 wheel 26 is located on the left of the plunger 50. As the carriage begins its printing stroke, the plunger 50 will be depressed as its beveled edge will be engaged by the teeth 42 on the stop wheel 26. The carriage will 60 continue its printing stroke until the particular stop rod 30 having alignment with the bumper 32 engages the bumper, when the carriage will, of course, be returned by the operator. On the return movement of the carriage, the stop wheel will engage the straight

edge of the plunger 50, and, since the grooves 40 are diagonally spaced on the circumference of the wheel, a groove will be directly in the path of the plunger which, by continued movement of the carriage, will have 70 sliding engagement within the groove, thus giving a consequent rotation to the stop wheel sufficient to bring another stop rod 30 of different length into alignment with the bumper.

It will be seen, therefore, that the carriage will have a printing stroke of a length which will vary as the length of the stop rods vary, and which will be changed on each return movement of the carriage through engagement 80 of the plunger 50 in the diagonal grooves 40. After a particular stroke of the carriage is secured, however, to agree with the size of the master sheets and copies to be worked upon, the indexing means may be discontinued by the handle 60 provided for that purpose which, on operation, will slide the block 54 towards the operator, thereby retracting the plunger 50. On the return movement of the carriage, therefore, rotation will 85 not be imparted to the stop wheel, and the pawl 36 will function to maintain that particular stop rod in alignment with the bumper as long as the plunger remains retracted. After the desired number of copies have been 90 duplicated, the plunger can be released by the operator and a printing stroke secured of a different length to agree with the size of the master sheet and the copies to be next 95 duplicated.

It is to be understood that I do not wish to be limited by the exact embodiment of the device shown, which is merely by way of illustration and not limitation, as various and other forms of the device will of course be 105 apparent to those skilled in the art without departing from the spirit of the invention or the scope of the claims.

I claim:

1. In a duplicating machine, in combination, a frame having a printing bed, a platen carriage adapted to travel over said bed in its printing stroke, means for arresting the movement of said carriage to secure a printing stroke of certain length including a bumper secured to said frame, a stop wheel secured to said carriage and adapted for rotation, stop rods secured to said wheel and spaced around the periphery thereof and adapted upon rotation of said wheel to be brought into alignment with said bumper, means for rotating said wheel by the return movement of said carriage and a wedge block for disconnecting said rotating means to maintain a selected rod in alignment with said bumper.

2. In a duplicating machine, in combination, a frame having a printing bed, a platen carriage adapted to travel over said bed in its printing stroke, means for arresting the movement of said carriage to secure a print-

- ing stroke of certain length including a bumper secured to said frame, a plurality of stop rods secured to said platen carriage and adapted for rotation to bring said rods into alignment with said bumper, means for rotating said rods by the return movement of said carriage and a wedge block for disconnecting said rotating means to maintain a selected rod in alignment with said bumper. 5

3. In a duplicating machine, in combination, a frame having a printing bed, a platen carriage adapted to travel over said bed in its printing stroke, means for arresting the movement of said carriage to secure a printing stroke of certain length including a bumper secured to said frame, a plurality of stop rods secured to said platen carriage and adapted for rotation to bring said rods into alignment with said bumper, a plunger 10 for causing rotation of said rods by the return movement of said carriage and means for retracting said plunger to maintain a selected rod in alignment with said bumper. 15

4. In a duplicating machine, in combination, a frame having a printing bed, a platen carriage adapted to travel over said bed, a bumper secured to said frame, a stop wheel secured to said carriage and adapted for rotation, stop rods secured to said wheel and spaced around the periphery thereof and adapted upon rotation of said wheel to be brought into alignment with said bumper for arresting the travel of said carriage, a plunger for causing rotation of said wheel by the return movement of said carriage and means for retracting said plunger to maintain a selected rod in alignment with said bumper. 20

5. In a duplicating machine, in combination, a frame having a printing bed, a platen carriage adapted to travel over said bed, a bumper secured to said frame, a stop wheel secured to said carriage and adapted for rotation, stop rods secured to said wheel and spaced around the periphery thereof and adapted upon rotation of said wheel to be brought into alignment with said bumper for arresting the travel of said carriage, means for causing rotation of said wheel comprising a plunger secured to said frame, and diagonal grooves on said wheel adapted to be engaged by said plunger on the return movement of said carriage. 25

6. In a duplicating machine, in combination a frame having a printing bed, a platen carriage adapted to travel over said bed, a bumper secured to said frame, a stop wheel secured to said carriage and adapted for rotation, stop rods secured to said wheel and spaced around the periphery thereof and adapted upon rotation of said wheel to be brought into alignment with said bumper for arresting the travel of said carriage, a plunger for causing rotation of said wheel by the return movement of said carriage, and a pawl 30 for locking said wheel in set position. 35

7. In a duplicating machine, in combination, a frame having a printing bed, a platen carriage adapted to travel over said bed, a bumper secured to said frame, a stop wheel secured to said carriage and adapted for rotation, and stop rods secured to said wheel and spaced around the periphery thereof and adapted upon rotation of said wheel to be brought into alignment with said bumper for arresting the travel of said carriage. 40

8. In a duplicating machine, in combination, a frame having a printing bed, a platen carriage adapted to travel over said bed, means for stopping the carriage at a point in its travel including a bumper on said frame, a plurality of stop rods secured to said carriage and a stop wheel adapted for rotation to bring a selected rod in alignment with said bumper. 45

9. In a duplicating machine, in combination, a frame having a printing bed, a platen carriage adapted to travel over said bed, means for stopping the carriage at a point in its travel including a bumper on said frame, a stop rod secured to said carriage and a pawl for locking said rod in alignment with said bumper. 50

10. In a duplicating machine, in combination, a frame having a printing bed, a platen carriage adapted to travel over said bed, means for stopping the carriage at a point in its travel including a bumper on said frame, a stop wheel secured to said carriage and provided with diagonal grooves, stop rods secured to said wheel for engagement against said bumper, and means for locking said wheel against rotation by engagement in said grooves. 55

11. In a device of the character described, in combination, a frame having a printing surface, a carriage adapted to travel over said surface, means for stopping the carriage at various points in its travel comprising a bumper secured to said frame, a stop wheel secured to said carriage and a plurality of stop rods of different lengths secured to said wheel. 60

12. In a device of the character described, in combination, a frame having a printing surface, a carriage adapted to travel over said surface, means for stopping the carriage at various points in its travel including a stop wheel secured to said carriage, grooves on said wheel, a plunger located on said frame and adapted to engage within said grooves during the travel of said carriage, and means for retracting said plunger. 65

13. In a duplicating machine, the combination of a printing bed, a carriage movable back and forth along said bed, a plurality of stops located in definite relation to each other for determining the length of printing stroke of the carriage, and means for placing any one of said stops in operative position. 70

14. In a duplicating machine, the combina- 75
